UNITED STATES PATENT OFFICE.

SIGMUND JOSEPH PENTLER, OF WAUSAU, WISCONSIN.

SHOE CONSTRUCTION.

1,311,356.

Specification of Letters Patent. Patented July 29, 1919.

Application filed February 27, 1918. Serial No. 219,415.

To all whom it may concern:

Be it known that I, SIGMUND JOSEPH PENTLER, a citizen of the United States, and resident of Wausau, in the county of Marathon and State of Wisconsin, have invented 5 certain new and useful Improvements in Shoe Construction; and I do hereby declare that the following is a full, clear, and exact description thereof.

10 My invention consists in certain new and useful improvements in shoes, particularly in the manner of securing the several parts of the same together.

At the present time it is customary to insert the inner sole sock lining after the shoe 15 has been lasted and the outer sole and heel added. This sock lining must obviously be cemented or otherwise secured in position to prevent wrinkling or the like, and inasmuch 20 as it is inserted as the final operation in the making of a shoe, it necessarily occupies a portion of the space intended for the wearer's foot.

It is one object of the present invention 25 to build the sock lining into the shoe at the same time that the middle sole is applied; this eliminates the heretofore necessary final operation of cementing the sock lining. Furthermore as this sock lining is in position 30 when the shoe is being lasted, it will not occupy any of the foot space within said shoe.

A further object of the invention is to 35 provide an improved arrangement for securing the shoe upper and the lining therefor to the lower portion or soles of the shoe.

With these and other objects and advantages in view which will become apparent as the description and operation progresses, 40 it will be seen that my shoe consists in certain novel combinations of parts which will be hereinafter more particularly described and claimed.

In the drawings:—

45 Figure 1 represents a side elevational view, partly in longitudinal section, of a shoe constructed in accordance with my invention.

Fig. 2 is a transverse sectional view 50 through the toe portion of my shoe.

Fig. 3 is a similar view through the heel portion.

Fig. 4 is a detail perspective view of the 55 combination middle sole and sock lining which forms a portion of the invention, and

Fig. 5 is a longitudinal sectional view

through a portion of a partially completed shoe.

Referring more particularly to the drawings it will be seen that the numeral 1 designates the upper of a shoe constructed in accordance with my invention having inner and outer cloth linings 2 and 3 respectively, a toe box 4 and a counter 5. This upper is secured by any one of the several methods 60 at present in use to a middle sole 6 or to an inner sole or sock lining 7 and said middle sole 6 is secured to an outer sole 8. The usual rubber or leather heel 9 is nailed to the heel portion of the outer sole and middle 70 sole.

As hereinbefore mentioned one of the most important features of this invention consists in applying the sock lining 7 practically coincident with the application of 75 the middle sole 6. To procure this in one operation the intermediate portion 7^a of the sock lining is stitched adjacent its opposite edges as at 10 to the intermediate portion 6^a of the middle sole 6, the toe and heel portions 7^b and 7^c respectively of the sock lining being free as illustrated by the dot and dash lines in Fig. 1 or in Fig. 4. The middle sole 6 is cut in the shape of a foot as is customary and is substantially the same size 80 as the outer sole 8; the sock lining on the other hand is cut on the insole pattern and consequently is considerably smaller than the middle sole although of the same configuration. 90

After the upper, including its linings 2 and 3 and toe and counters has been fashioned it is placed on a last and then secured to the middle sole or to the sock lining 6. Fig. 1 illustrates the upper stitched 95 as at 11 to the middle sole 6 while the inner lining 2 and the edges of the toe and heel boxes are bent inwardly and cemented, stitched or otherwise secured to the under side of the sock lining. The outer lining 3 of the upper, it will be noted from Fig. 1, terminates substantially at the inner edge of the toe box and similarly at the upper edge of the heel box. 100

In Fig. 5 the upper 1' as well as the heel 105 box 5' and the lining 2' is "lasted in" and secured as at 12 to the under surface of the sock lining 7'. In this form of my invention the middle sole 6' and sock lining 7' are secured together as in the form of shoe 110 shown in Fig. 1.

The outer sole 8 is stitched as at 13 or

otherwise secured to the middle sole 6 or 6' as the case may be. When the upper is attached to the middle sole as in Fig. 1 a finishing strip 14 is preferably disposed 5 over the outwardly extending portion 15 of the upper and secured in position by the stitches 13 which attach the outer sole to the middle sole. It is obvious, however, that the several parts of the shoe may be 10 secured together not only by the method illustrated, but by the Goodyear welt or by any other preferred process.

Before the heel portion 7^c of the sock lining has the inwardly extending parts of the 15 counter and lining 2 cemented or otherwise attached thereto, the heel 9 is nailed in place. The heel portion 7^c being free, it may be moved away from the adjacent portion of the middle sole so that the nails 20 16 may be clenched as they project through the latter, or a temporary metallic heel plate may be placed between the heel portions of the middle sole and sock lining to turn the nails 16 as they are driven thereagainst. Thus a nailless heel seat is produced.

There are several very material advantages to be derived from the securement of the sock lining or inner sole and the middle 30 sole together prior to the incorporation of the latter into a shoe in addition to those already enumerated. For instance, the sock lining increases the stiffness of the middle

sole at its weakest point and thus a thinner or cheaper grade of material may be used 35 for such middle sole. And the edge of the sock lining prevents the upper from falling in adjacent its attachment to the middle sole and thereby retains the shoe in proper shape.

I claim:—

In a boot or shoe, an upper, a lining therein, a middle sole of comparatively thin and flexible material, a sock lining of thin and flexible material and smaller in size 45 than the middle sole, an independent row of stitching securing each longitudinal edge of the shank of the sock lining to the shank of the middle sole to stiffen both the sock lining and middle sole and decrease their 50 flexibility, the edge of the sock lining being equally spaced from the edge of the middle sole, the heel and toe portions of the former being free, means for securing the lower edge of the upper to the portion of the middle sole disposed outwardly of the edge of the sock lining, the lower edge of the lining of the upper being disposed beneath the edge portions of the sock lining, and an outer sole of the same size as the middle 55 sole and secured thereto.

In testimony that I claim the foregoing I have hereunto set my hand at Milwaukee, in the county of Milwaukee, and State of Wisconsin.

SIGMUND JOSEPH PENTLER.
